(57) **CLAIM**

An ornamental design for a charge station for an electric vehicle, as shown and described.

DESCRIPTION

The file of this patent contains at least one drawing executed in color. Copies of this patent with color drawing(s) will be provided by the Office upon request and payment of the necessary fee.

FIG. 1 is a front perspective view of an embodiment of the charge station for an electric vehicle;

FIG. 2 is a front view of the embodiment of FIG. 1, the rear view being a mirror image thereof;

FIG. 3 is a side view of the embodiment of FIG. 1, the opposite side view being a mirror image thereof;

FIG. 4 is a top view of the embodiment of FIG. 1;

FIG. 5 is a front perspective view of another embodiment of the charge station for an electric vehicle;

FIG. 6 is a front view of the embodiment of FIG. 5, the rear view being a mirror image thereof;

FIG. 7 is a side view of the embodiment of FIG. 5, the opposite side view being a mirror image thereof; and,

FIG. 8 is a top view of the embodiment of FIG. 5.
